(57) **CLAIM**

The ornamental design for an absorbent article package, as shown and described.

DESCRIPTION

The file of this patent contains at least one drawing/photograph executed in color. Copies of this patent or patent application publication with color drawing(s) will be provided by the Office upon request and payment of the necessary fee.

FIG. 1 is a front, right and top perspective view of an absorbent article package showing our new design;

FIG. 2 is a view of the front side of the package of FIG. 1;
FIG. 3 is a view of the right side of the package of FIG. 1;
FIG. 4 is a view of the back side of the package of FIG. 1;
FIG. 5 is a view of the left side of the package of FIG. 1;
FIG. 6 is a view of the top side of the package of FIG. 1; and
FIG. 7 is a view of the bottom side of the package of FIG. 1.

FIG. 8 is a front, right and top perspective view of a second embodiment of an absorbent article package showing our new design;

FIG. 9 is a view of the front side of the package of FIG. 8;
FIG. 10 is a view of the right side of the package of FIG. 8;
FIG. 11 is a view of the back side of the package of FIG. 8;
FIG. 12 is a view of the left side of the package of FIG. 8;
FIG. 13 is a view of the top side of the package of FIG. 8; and,

FIG. 14 is a view of the bottom side of the package of FIG. 8.
